UNITED STATES PATENT OFFICE.

WILLIAM HENRY WEIGAND, OF TROJAN, SOUTH DAKOTA.

ORE-CLASSIFIER.

1,192,806.

Specification of Letters Patent. Patented July 25, 1916.

Application filed June 19, 1914. Serial No. 846,080.

To all whom it may concern:

Be it known that I, WILLIAM H. WEIGAND, a citizen of the United States, and a resident of Trojan, in the county of Lawrence and State of South Dakota, have invented a new and Improved Ore-Classifier, of which the following is a full, clear, and exact description.

The invention relates to ore classifiers of the rotary type.

An object thereof is to provide a simple, inexpensive and efficient classifier whereby the process of classification can be controlled by varying the discharge opening and also the liquid level.

A further object of the invention is to provide a classifier wherein the crushed ore is uniformly distributed along its path of travel, so as to thin gradually and increase its surface as it approaches the end of its travel.

A further object of the invention is to provide a classifier in which the particles of the ore are continuously overturned in such a manner as to allow the slime particles to become free and flow away.

A still further object of the invention is to provide a classifier whereby a large tonnage of ore can be handled.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views, and Figure 1 is a plan view of an embodiment of my invention partly sectioned to show the details of construction; Fig. 2 is a side elevation thereof; Fig. 3 is a section on line 3—3, Fig. 1; Fig. 4 is a similar section showing the agitating means removed; and Fig. 5 is an enlarged sectional view of the central discharge nozzle.

Referring to the drawings, 6 represents a tank which converges from the edges to the central part thereof and is preferably shallow and frusto-cone shaped. The converging surface forming the tank has two conical portions 7 and 8, of which 8 is the outer portion and flatter than the inner portion. The inner portion 7 is associated with an inwardly projecting tubular portion 9 which does not extend to the upper edge of the

tank and constitutes the central outlet from the said tank 6. The tank is provided with a support 10, which is preferably at the outer edge of the tank, and, as shown in the drawings, is cylindrical in shape. The lower edge of the support is preferably level with the lowermost point of the tank, so that the whole can be properly supported by a suitable horizontal support. The support 10 is provided peripherally with a circular trough 11 properly inclined to cause a natural flow therein. This trough or launder forms the outer passage from the tank 6.

Rigidly secured to the tubular member 9 is an annular table 12 on which is rotatably mounted a worm gear 13 meshing with a worm 14 which is associated with pulleys 15 whereby the same and, therefore, the worm wheel, may be rotated. Rigidly secured to the worm wheel 13 are downwardly extending brackets 16. The lower end of each bracket extends substantially from the tubular member 9 to the periphery of the conical portion 7 of the tank, and preferably disposed parallel to said conical portion 7 of the tank. Rigidly secured to said lower end of each of the brackets is an arm 17 extending from the tubular part 9 to the outer edge of the tank and disposed parallel to the surface forming the tank and spaced therefrom. Positioned between the arm 17 and the surface forming the tank is a series of spirally-shaped blades 18 carried by said arm, and which blades are so disposed relatively to the direction of rotation of said arms as to cause the substance within the tank to flow from the central part thereof toward the outer periphery, as can be easily seen from Fig. 1.

An annular trough 19 is mounted on the brackets 16 so that the upper edge of said trough is substantially level with the upper edge of the tank 6. Said trough forms the inlet for the crushed ore and the liquid, from where it is discharged into the tank 6 through openings 20 provided at the bottom of said trough adjacent the outer periphery. It will be noted that this trough rotates with the agitating mechanism and, therefore, a more even distribution of the ore and liquid into the tank 6 is obtained.

Mounted within the tubular member 9 of the tank is a central outlet nozzle 21, which has the lower end slightly reduced and threaded, and whereto a suitable connection 22 can be made. The upper end of the nozzle is preferably flush with the tubular mem-

ber 9. Associated with the said upper end of the nozzle is a series of annular frusto-cone shaped segments 23, of varying sizes, removably associated with one another and with said nozzle and therewith forming a funnel. The flared part of the funnel is above the tubular member 9 within the tank 6, which flared portion can be varied in diameter by removing one or more of said annular members 23 and thereby lowering said funnel with reference to the upper edge of the tank. By removing one or more of said annular members 23 the central discharge level is varied, and also the diameter of the discharge, as can be easily seen.

By means of the annular segments 23 a more perfect control of the product is obtained, as coarser or finer slimes are obtained by varying the height of the flared part of the funnel within the tank 6. It will also be remarked that the suspended slime must be raised through a great volume of liquid, and it discharges on a large circumference formed by the edge of the upper annular member 23. The agitating mechanism, which is formed of the radial arms 17 suspended from the table 12, when rotated thereon, causes a greater overturning action of the settled particles, by means of the curved 30 blades or vanes, allowing thereby the finer particles to free themselves; and, due to the agitation caused by the movement of the mechanism and the current of liquid created thereby in the tank, said particles are carried from the central discharge, *i. e.*, from the funnel formed by the annular member 23. The annular feed formed by the trough 19, which rotates with the agitating apparatus, causes the liquid to be fed into the tank 40 in thin streams at the bottom of the greater circumference of said trough, thus facilitating the immediate separation into its classes, and to do so under conditions more favorable than where feed of crushed ore and liquid is applied in one place. The trough 19 being of great diameter, and, consequently, of great circumference, has a large capacity adapted to effectively and uniformly distribute over a large circular area 50 a large quantity of the ore and fluid and lessen the tendency of a large quantity of feed to violently splash or unduly agitate and stir up particles that are desired to be settled.

55 The purified sand is discharged to the trough 11 to which sand or settled ore is raked by action of the blades 18 carried by the arms 17, and which blades cause said settled ore to travel from the central part of the tank to the outer. In view of the peculiar shape of the blades or vanes 18, the path of travel of the discharged ore is more like an involute curve than a straight line. This long path of travel of the ore, assisted by the repeated overturning of the same by the

blades, gives the settled sand further chance to become free from finer particles which are to be discharged centrally through the funnel. It will also be noted that, due to the movement of the ore from the central part 70 to the outer part of the tank, the layer becomes thinner and thinner as it approaches the outer discharge, due, of course, to being spread over a larger area, this, necessarily, further perfecting the classification. The 75 settled sand or heavier particles which are caused to ascend to the steeper sides of the cone-shaped tank, while submerged all or part of the distance, as may be determined by the height of the central discharge formed 80 by the funnel, on reaching the flatter section of the tank, *i. e.*, the part 8, will have less tendency to move back, that is, to the central part of the tank. If desired the settled sand may be allowed to be discharged in a dry 85 condition, no wash being given, due to the great path of travel.

From the above description it will be noted that the process of classification of the ore consists in conveying the crushed ore 90 and liquid into a concave vessel wherein the discharged ore is agitated, the suspended particles being discharged at the central part, while the settled particles are caused to ascend toward the periphery of the tank in 95 a sinuous path.

From the foregoing description, taken in connection with the accompanying drawings, the advantage of the construction and method of operation of the apparatus shown 100 will be readily understood by those skilled in the art to which the invention pertains, and while I have described the principle of operation, together with the device and method of making the same, which I now 105 consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. In a classifier, a concave vessel having a raised central outlet, a nozzle in said outlet, a plurality of annular, upwardly-expanding frustocone-shaped members removably associated with each other and with said nozzle and forming therewith a funnel, the level and size of which funnel in the vessel may be varied by means of said removable frustocone-shaped members, and a stirring mechanism associated with the vessel and adapted to direct the mass within the vessel from the central outlet toward the 115 periphery of the vessel.

2. In an ore classifier, a concave vessel having a raised, central tubular member forming a central outlet of the vessel, a table associated with the tubular member, means 120

125

- for rotating the table, brackets from said rotating means, arms associated with said brackets and extending parallelly to the surface of the vessel, blades on said arms adapted to scrape the surface of the vessel and direct the mass therein toward the periphery of the vessel, and an annular distributer for said vessel carried by said brackets.
- 10 3. In an ore classifier, a concave vessel in the shape of an inverted cone, said vessel having a central outlet, interengaging, upwardly-expanding frustoconical sections associated with the outlet for varying its level and diameter within the vessel, a stirring mechanism associated with the vessel, means on the stirring mechanism to scrape the surface of the vessel and direct the mass in the vessel toward the raised periphery of the
- 15 same, and an annular feed for said vessel carried by the stirring mechanism, said vessel having a peripheral outlet.
- 20 4. In a classifier, a concave vessel in the shape of an inverted cone having a flat cone portion adjacent the periphery thereof, said vessel having a central outlet, a plurality of upwardly-expanding, frustoconical members
- 25 removably associated with each other and with said central outlet whereby the level and the diameter of the central outlet may be varied, a stirring mechanism associated with the vessel, blades carried by the stirring mechanism for scraping the surface of the vessel and direct the mass in the vessel over the central part thereof toward the raised periphery of the vessel, and an annular feed for said vessel carried by the stirring mechanism.
5. In an ore classifier, a concave vessel having a central and a peripheral outlet, frustoconical sections increasing in size upwardly engaging the central outlet, whereby the size and level of the central outlet may be varied, a stirring mechanism in said vessel, and an annular distributer adjacent the central outlet.

In testimony whereof I have signed my name to this specification in the presence of two subscribing witnesses.

WILLIAM HENRY WEIGAND.
